STABILIZATION OF ORGANIC SUBSTANCES

Roger W. Watson, Chicago, Ill., and Clarence M. Loane, Hammond, Ind., assignors to Standard Oil Company, Chicago, Ill., a corporation of Indiana

No Drawing. Application March 28, 1946,
Serial No. 657,892

13 Claims. (Cl. 44—74)

1

The present invention relates to the stabilization of organic substances against oxidative deterioration in the presence of metals which catalyze the oxidation, for example copper, vanadium, chromium and the like. More particularly, the present invention is directed to the stabilization of petroleum products against oxidative deterioration in the presence of copper or compounds thereof and to such stabilized products.

Organic substances such as petroleum products, for example, motor fuels, naphthas, fuel oils, electrical insulating oils, lubricating oils, greases, waxes and asphalts, compounded lubricants, synthetic hydrocarbon oils, vegetable oils, animal oils, marine oils, vegetable juices, textile fibers, antioxidants, rubber and rubber products, soaps, etc. are susceptible to oxidative deterioration which is accelerated by the presence of metals which are oxidation catalysts, for example, copper, vanadium, chromium, etc. or compounds thereof.

An example of such oxidative deterioration is the formation of gum and/or color under storage conditions of certain types of motor fuels, particularly those obtained from cracking processes. In order to inhibit such gum and/or color formation, it has been common practice to add to such fuels various types of antioxidants such as for example, aminophenols, substituted aminophenols, naphthols, aromatic hydroxy compounds, hardwood tar distillates and other known antioxidants. It has been observed that when motor fuels containing antioxidants are stored in metal containers or come in contact with metal surfaces containing copper or copper alloys, the inhibiting effect of the antioxidant is decreased to the point where such fuels form gum in spite of any antioxidant they may contain. The deterioration of antioxidants is also encountered in fuels which have been subjected to the copper chloride sweetening process.

It is an object of the present invention to provide a method of inhibiting the oxidative deterioration of organic substances in the presence of metals which are oxidation catalysts. Another object of the invention is to provide a class of inhibitors which, when added to an organic substance normally susceptible to oxidative deterioration in the presence of metals which are oxidation catalysts, will inhibit or suppress the activity of such metals. Another object of the invention is to provide a new class of metal deactivators. Another object of the invention is to provide a class of organic compounds, which when added to an organic substance containing an antioxidant, will increase the efficiency of the antioxidant in

the presence of metals or compounds thereof which are oxidation catalysts. Still another object of the present invention is to inhibit the oxidative deterioration of petroleum hydrocarbons containing or in contact with metals or metal compounds which catalyze such oxidative deterioration. Other objects and advantages will become apparent from the following description thereof.

10 We have discovered that the oxidative deterioration of organic substances can be effectively inhibited or suppressed by adding to such organic substances an organic dithiooxamide. These organic dithiooxamides have the following general structures:

20 in which R^1 and R^2 are hydrogen or organic groups such as aliphatic, cyclic aliphatic, aromatic or heterocyclic groups. The substituents R^1 and R^2 may be the same or different groups and may contain substituents such as alkyl, aryl, alkoxy, aryloxy, hydroxy, halogen, nitro, cyano, carboxyl, and amino groups. The organic dithiooxamides employed in the present invention include linear condensation products resulting from the reaction of a dithiooxamide with a polyamino compound containing at least two primary amino nitrogen atoms, for example alkylene polyamines such as ethylene diamine, diethylene triamine, triethylenetetraamine, tetraethylene pentamine, propylene diamine, and other polyamino compounds, for example aminopiperazines, tolylenediamine, diaminobenzene, diaminopyridine, etc. These linear condensation products may be represented by the general formula:

40 wherein R^1 and R^2 are as above defined, n is at least one, and Z is a residue from a polyamino compound; that is, the residue obtained from a polyamino compound when two primary amino groups are removed.

Many organic substances are inhibited against oxidative deterioration by the addition thereto of small amounts of antioxidants. However, in the presence of certain metals, such as for example copper, vanadium, chromium, iron, cobalt or compounds thereof, the oxidation inhibiting effect of such antioxidants is materially reduced. The above described class of compounds are particu-

larly effective as metal deactivators in suppressing or inhibiting the deteriorating effect of such metals on antioxidants.

The dithiooxamides are readily prepared by reacting cyanogen with hydrogen sulfide according to the following equations:

The nitrogen substituted derivatives of the dithiooxamide are obtained by heating the dithiooxamide at a temperature of about 200° F. with an amine. This reaction is represented by the following equation:

The linear condensation products above described can be readily prepared by reacting an organic dithiooxamide with a polyamine. This is illustrated by the following equation in which dimethyldithiooxamide is reacted with ethylene diamine:

The amount of the inhibitor added to the organic material to be protected against oxidative deterioration will vary with the amount of catalyst present and the activity of such metal. A small amount sufficient to inhibit the oxidative deterioration should be employed, for example from about 0.0001% to about 1%, and preferably from about 0.001% to about 0.1% of the inhibitor based on the organic substance. It is to be understood of course that greater amounts can be employed as conditions warrant.

Specific examples of organic dithiooxamides which can be employed in accordance with the present invention are:

Dithiooxamide
N-methyldithiooxamide
N-ethyldithiooxamide
N-propyldithiooxamide
N-isobutyldithiooxamide
N-cyclohexyldithiooxamide
N-octyldithiooxamide
N-dodecyldithiooxamide
N-hydroxyethylidithiooxamide
N-aminoethylidithiooxamide
N-ortho-hydroxyphenyldithiooxamide
N,N'-diisopropylidithiooxamide
N,N'-di-o-hydroxyphenyldithiooxamide
N,N'-di(aminoethyl) dithiooxamide
N,N'-di(hydroxyethyl) dithiooxamide
N,N'-di-o-aminotolylidithiooxamide
N-methyl, N'-allyldithiooxamide
N-butyl, N'-phenyldithiooxamide

Condensation compounds formed by the reaction of any of the above compounds with one of the following polyamines:

- 5 Ethylene diamine
Propylene diamine
B,B',B'' triaminotriethyl amine
Diethylene tetramine
Diethylene triamine
Dipropylene triamine
Tolylene diamine
Tetraethylene pentamine
B,B',B'' triaminotripropylamine
Phenylene diamine

While all of the organic dithiooxamides are effective inhibitors, it is not to be implied that all are equivalent since the specific activity of the various compounds varies to some extent.

The effectiveness of the herein-described compounds as inhibitors against oxidative deterioration, particularly in the presence of metal catalysts, is illustrated by the following data obtained by subjecting a motor fuel containing an antioxidant, in the presence of a metal or metal compound, to the A. S. T. M. method for determining the stability of gasoline by accelerated oxidation. This test method having A. S. T. M. designation D525-42T is fully described on page 965 of the A. S. T. M. Standards of 1942, Part III. In mak-

ing this test, the blank was a motor fuel containing about 0.01% butylaminophenol as the antioxidant.

50	Sample	Induction Period, mins.		
		No Copper	Soluble Copper	Metallic Copper
Blank		635-680	85-100	155
Blank+0.005% Commercial Metal Deactivator			790	265
Blank+0.005% Thioacetamide			250	---
Blank+0.005% N,N'-Dimethyldithiooxamide			665	745

The "soluble copper" employed in the above test was copper oleate used in a concentration of four milligrams per liter, and the "metallic copper" was eighteen inches of No. 18 copper wire in each test bomb.

As shown by the above data, the dithiooxamide very effectively maintained the inhibiting effect of the antioxidant in the presence of soluble copper as well as metallic copper. The commercial metal deactivator however was ineffective in the presence of metallic copper.

While we have described our invention in connection with the stabilization of motor fuels, it is not limited thereto but is applicable to the stabilization of organic substances, such as for example those hereinbefore mentioned. When employed in lubricants, such as lubricating oils and greases, turbine oils, insulating oils and the like,

the herein-described metal deactivators can be used in conjunction with antioxidants, anti-rust compounds, pourpoint depressants, detergents, anti-wear agents, anti-foam agents, bearing corrosion inhibitors, etc.

While we have disclosed the preferred embodiments of our invention and the preferred modes of carrying out the same in effect it will be readily apparent to those skilled in the art that many variations and modifications may be made without departing from the spirit of our invention.

We claim:

1. An oleaginous organic material selected from the group consisting of a hydrocarbon oil and a fatty oil, which is normally susceptible to oxidative deterioration in the presence of a metal and compounds thereof which catalyze said oxidative deterioration, containing an organic dithiooxamide in small but sufficient quantities to suppress the oxidative catalyzing effect of said metal and compounds thereof.

2. A composition as described in claim 1 in which the dithiooxamide is an alkylidithiooxamide.

3. A composition as described in claim 1 in which the dithiooxamide is dimethyldithiooxamide.

4. A composition as described in claim 1 in which the dithiooxamide is an aryldithiooxamide.

5. A composition as described in claim 1 in which the dithiooxamide is di(o-amino-phenyl)dithiooxamide.

6. An oleaginous organic material selected from the group consisting of a hydrocarbon oil and a fatty oil containing a small amount of an antioxidant normally effective in inhibiting the oxidative deterioration of said organic material in the absence of a metal and compounds thereof, which normally catalyzes the oxidative deterioration of said organic material and which normally decreases the effectiveness of said antioxidant, and an organic dithiooxamide, said organic dithiooxamide being used in small but sufficient quantities to deactivate said oxidation catalyst.

7. A composition as described in claim 6 in

which the organic dithiooxamide is a dialkyldithiooxamide.

8. A normally liquid petroleum hydrocarbon, normally susceptible to oxidative deterioration in the presence of a metal and compounds thereof which normally catalyze said oxidation, containing an organic dithiooxamide in small but sufficient quantities to suppress the catalyzing effect of said oxidation catalyst.

9. A composition as described in claim 8 in which the organic dithiooxamide is a dicycloalkylidithiooxamide.

10. A composition as described in claim 8 in which the organic dithiooxamide is a dialkyldithiooxamide.

11. A composition as described in claim 8 in which the organic dithiooxamide is dimethyldithiooxamide.

12. A composition as described in claim 8 in which the petroleum hydrocarbon contains in addition to said organic dithiooxamide a small but sufficient amount of an antioxidant normally effective to inhibit the oxidative deterioration of said petroleum hydrocarbon in the absence of the oxidation catalyst but normally ineffective to inhibit said deterioration in the presence of said oxidation catalyst.

13. A composition as described in claim 9 in which the petroleum hydrocarbon contains from about 0.0001% to about 1% of said organic dithiooxamide.
